Primary Examiner — Mark A Goodwin*(74) Attorney, Agent, or Firm* — Calfee, Halter & Griswold LLP(57) **CLAIM**

The ornamental design for a stabilizer pad, as shown and described.

DESCRIPTION

FIG. 1 is a top perspective view of an exemplary embodiment of a stabilizer pad looking at the front side;

FIG. 2 is a top perspective view of the stabilizer pad of FIG. 1 looking at the rear side;

FIG. 3 is a bottom perspective view of the stabilizer pad of FIG. 1 looking at the rear side;

FIG. 4 is a bottom perspective view of the stabilizer pad of FIG. 1 looking at the front side;

FIG. 5 is a top plan view of the stabilizer pad of FIG. 1; FIG. 6 is a rear view of the stabilizer pad of FIG. 1; and, FIG. 7 is a right side view of the stabilizer pad of FIG. 1. The left side view of the stabilizer pad is a mirror image of the right side view.

The bottom of the stabilizer pad is flat and devoid of surface ornamentation and, thus, a bottom plan view is omitted. The portions of the Figures shown in phantom lines are either unclaimed boundary lines or for illustrative purpose only, and no phantom line forms a part of the claimed design.
